[57] CLAIM

The ornamental design for a shoe sole plate bottom, as shown and described.

DESCRIPTION

FIG. 1 is a bottom plan view of a shoe sole plate bottom showing my new design;

FIG. 2 is a side elevational view of one side of the sole plate shown in FIG. 1;

FIG. 3 is a side elevational view of the other side of the sole plate shown in FIG. 1;

FIG. 4 is a front elevational view of the sole plate shown in FIG. 1;

FIG. 5 is a rear elevational view of the sole plate shown in FIG. 1;

FIG. 6 is a cross-sectional view of the sole plate as viewed along line 6—6 of FIG. 1 with distal elements not shown for clarity; and

FIG. 7 is a cross-sectional view of the sole plate as viewed along line 7—7 of FIG. 1 with distal elements not shown for clarity.

FIG. 3

FIG. 7

FIG. 6

FIG. 5

FIG. 4
